UNITED STATES PATENT OFFICE

JOHN H. PETERSON, OF BIRMINGHAM, ALABAMA

DESIGN FOR GATEWAY ROAD SIGN

Application filed July 9, 1930. Serial No. 36,303. Term of patent 14 years.

To all whom it may concern:

Be it known that I, JOHN H. PETERSON, a citizen of the United States, residing at Birmingham, in the county of Jefferson and State of Alabama, have invented a new, original, and ornamental Design for a Gateway Road Sign, of which the following is a specification, reference being had to the accompanying drawings, forming part thereof.

Fig. 1 is a front elevational view of gateway road sign showing my new design.

Fig. 2 is an end elevational view thereof.

I claim:

The ornamental design for a gateway road sign, as shown.

JOHN H. PETERSON.
